UNITED STATES PATENT OFFICE.

JOHN H. JOHNSTON, OF NEW YORK, N. Y.

DESIGN FOR A SPOON.

SPECIFICATION forming part of Design No. 20,495, dated February 3, 1891.

Application filed December 29, 1890. Serial No. 376,132. Term of patent 7 years.

To all whom it may concern:

Be it known that I, JOHN H. JOHNSTON, a citizen of the United States, residing at New York city, State of New York, have invented 5 a new and ornamental Design for Spoons, of which the following is a description.

The purpose of the invention is to produce a unique and ornamental spoon the design of which will suggest to the mind of the observer the quaint early history, real or imaginary, of the city of New York and Manhattan Island.

The design is represented in the accompanying drawing, which shows a spoon having 15 a conventional bowl and stem or handle extending from it. Upon the upper surface of the enlarged or flattened extremity of the handle is a representation in relief of Dietrich Knickerbocker, the fictitious author of 20 the "History of New York." The celebrated author is seated at an old-fashioned desk, the folding lid of which has been turned down to afford the table-surface of the desk. He is clad in the long-tailed frock coat, knee- 25 breeches, buckle-shoes, and stockings of the period. The hair is tied back in a queue. The head is well developed and a pair of spectacles rest upon his nose. He is leaning forward upon the desk, some loose papers being 30 under his arm and a quill pen in his hand. The foot toward the observer is thrown back and rests upon the ball. The inclined sides or edges of the desk lead up to the shelf-like

rear of the top of the desk, and a number of volumes are arranged thereon. The right-hand front corner of the desk is turned toward the observer and is indicated as having several drawers therein. Just back of the figure and extending along above the shoulder and arranged in a line conforming to the outward 35 curve of the handle at this point are ornamental letters forming the words "New York." On the face of the handle between the word "New" and the bowl is an old-fashioned long-stemmed Dutch pipe crossed with a cane. 40

In the drawings, A represents the bowl of the spoon; B, the slender part of the handle extending therefrom; C, its flattened enlarged end, and D, the representation of Dietrich Knickerbocker seated at his desk, as above 45 described.

It has been thought unnecessary to further 50 letter the design, as its general appearance and detail are obvious from the accompanying drawing.

I claim as my invention and desire to secure by Letters Patent—

The design for spoons herein described and illustrated.

In witness whereof I have hereunto signed 60 my name in the presence of two subscribing witnesses.

JOHN H. JOHNSTON.
